Primary Examiner — Jennifer L Watkins*(74) Attorney, Agent, or Firm* — Morris, Manning & Martin, LLP; Bryan D. Stewart; Daniel T. Begasse**CLAIM**

The ornamental design for a joint stabilization knee sleeve, as shown and described.

DESCRIPTION

FIG. 1 is a perspective view of an exemplary joint stabilization knee sleeve;

FIG. 2 is a front view of an exemplary joint stabilization knee sleeve;

FIG. 3 is a rear view of an exemplary joint stabilization knee sleeve;

FIG. 4 is a right side view of an exemplary joint stabilization knee sleeve;

FIG. 5 is a left side view of an exemplary joint stabilization knee sleeve;

FIG. 6 is a top view of an exemplary joint stabilization knee sleeve; and,

FIG. 7 is a bottom view of an exemplary joint stabilization knee sleeve.

The broken lines depict portions of a joint stabilization knee sleeve and form no part of the claim.
